UNITED STATES PATENT OFFICE.

JOSEPH HARRIS, OF WHEATON, ILLINOIS, ASSIGNOR TO W. H. MINER, INC., OF CHICAGO, ILLINOIS, A CORPORATION OF DELAWARE.

DRAFT-RIGGING-KEY RETAINER.

Application filed October 17, 1925. Serial No. 62,971.

This invention relates to improvements in draft rigging key retainers.

An object of the invention is to provide simple and reliable means which may be economically manufactured for retaining coupler or other draft rigging keys in place, so designed that ready removal of the keys is provided for, and wherein danger of accidental removal of such keys is positively prevented.

Another object of the invention is to provide means of the character indicated in the foregoing, wherein are utilized the usual stop lug plates or castings as a part of the retaining means for the keys without any substantial increase in the cost of manufacture of said plates and without in any way altering the mode of application of such parts to the draft sills, whereby the same may be used with the usual sills without change.

A further object of the invention is to provide means for retaining draft gear keys in assembled relation with the draft rigging, wherein draft lugs are used as a part of the retaining means and wherein the retaining means cooperates with the opposite ends of the keys to limit endwise displacement thereof, whereby a plain, unheaded key may be utilized instead of the usual headed key so that the decreased cost of the plain key over the key of the headed type will more than offset the slight additional cost incident to the changes in the draft lugs or plates.

Another object of the invention is to provide retaining means cooperating with the opposite ends of a plain, headless draft key, wherein the retaining means may be readily removed to provide for endwise withdrawal of the key outwardly of the sills on either side thereof, thereby greatly facilitating removal of the key in case it becomes wedged or removal thereof is obstructed in one direction.

Other objects and advantages of the invention will more fully and clearly appear from the description and claims hereinafter following.

In the drawing forming a part of this specification, Figure 1 is a side elevational view of a portion of a railway draft rigging, showing my improvements in connection therewith, the end sill being shown in section. Figure 2 is a vertical, transverse,

sectional view corresponding substantially to the line 2-2 of Figure 1. And Figure 3 is a vertical, transverse, sectional view through one of the draft sills of a car underframe, showing a different embodiment of the invention.

In said drawing, referring first to the embodiment of the invention illustrated in Figures 1 and 2, 10-10 indicate channel-shaped center or draft sills of a railway car underframe, provided with the usual front and rear sets of stop lugs, the front stop lugs only being illustrated in the drawing, the same being designated by 11-11. The inner end portion of the drawbar is designated by 12 to which is operatively connected a hooded yoke 13 by means of a transverse key 14. The yoke and the drawbar are provided with aligned openings adapted to receive the key 14, and the stop lugs 11 are in the form of castings as shown, having key receiving openings 15 therein. The openings 15 are reinforced by outwardly projecting flanges 16, accommodated within slotted openings 17 in the draft sills 10. The openings 17 are arranged in transversely aligned pairs. The stop lug castings 11 are preferably secured to the draft sills in the usual manner by a plurality of rivets 18.

In carrying out my invention, as illustrated in Figures 1 and 2, I employ a key of the headless type for attaching the drawbar 12 to the yoke 13, the opposite ends of the key working in the slots 15 of the stop castings. The key 14 is preferably in the form of a flat section of a bar. As most clearly shown in Figure 2, the reinforcing flanges 16 of the key receiving openings of the stop castings 11 project outwardly slightly beyond the planes of the outer sides of the corresponding draft sills. The upper horizontal section of each reinforcing flange 16 is provided with a laterally projecting central enlargement 19 extending beyond the corresponding outer end of the key 14. A retaining angle member 20 is supported by the flange section 19 of each stop casting 11, one of the flanges of the angle member 20 being disposed horizontally and secured to the upper face of the section 19 by any suitable means such as bolts 21 extending through aligned openings in the horizontal flange and the section 19. The other flange of the angle member 20 is vertically dis-

posed and overhangs the corresponding end of the key 14. As shown in Figure 2, the depending flanges of the angle members 20 are so located that there will be a slight clearance between the same and the corresponding outer end of the key 14. The sections 19 of the flanges 16 of the stop castings 11 are preferably counter-sunk to receive the heads of the bolts 21 so that the free movement of the key longitudinally of the sills in the slots 15 will be unobstructed. As most clearly shown in Figure 1, the depending flanges of the angle members 20 are of such a width lengthwise of the car as to at all times overlap a portion of the corresponding end of the key 14 during the different operative positions of the latter. As will be evident, the angle members are readily detachable by removing the bolts 21, whereby the key 14 may be removed in a direction outwardly of the sills.

In case it is desired to remove or replace the key 14, either one or both of the angle members 20 may be detached. As the angle members 20 are relatively heavy and are held to the draft lugs by the bolts 21, there is no danger of the angle members being broken or sheared off due to forces exerted by the lateral thrust of the key 14. It will be evident that by making both of the angle members removable and utilizing a headless key, the key may be driven out in either direction. This is of extreme importance where removal of the key is prevented in one direction by an obstruction or by the key becoming jammed in the openings of the drawbar and yoke.

Referring next to the embodiment of the invention illustrated in Figure 3, 10 indicates one of the draft sills of a railway draft rigging, 11 the stop lug and 14 a key of the headless type, these parts being identical with the parts 10, 11 and 14, described in connection with Figures 1 and 2. The draft lug 11 is provided with a laterally projecting flange section 19 identical with the flange section 19 hereinbefore described. In this instance, the retaining member is in the form of a bendable sheet metal strip of suitably heavy gauge, the same being indicated by 120. The strip 120 is preferably fixed to the upper side of the section 19 of the flange of the stop lug and may be secured by any suitable means, rivets 121 being preferably employed. The bendable strip 120 has a depending portion 122 forming an abutment for the corresponding outer end of the key 14. In practice, the gauge of the metal will be heavy enough so that the bent down flange will resist outward pressure from the key. The depending portion 122 is slightly spaced from the corresponding end of the key to provide for a certain amount of lateral play of the latter. The position of the section 122 of the strip 120 when the strip

as applied to the stop castings is indicated in dotted lines in Figure 3, the same being disposed in the plane of the main body portion of the strip. In this position of the section 122, the opening 15 of the stop lug 70 is unobstructed and the key may be readily inserted. After the key has been assembled with the draft rigging, the section 122 of the strip is hammered or bent down, from the dotted line position shown to the full line 75 position, in overhanging relation to the corresponding end of the key. It will be evident that when it is desired to remove the key, it is merely necessary to bend the section 122 of the strip 120 upwardly to the dotted line position shown. The key may then be removed by driving the same outwardly of the sills in either direction.

Although I have herein shown my improvements applied to stop lug castings of a draft rigging, it will be evident that the same may be employed in connection with what are commonly known as the "Farlow" attachments, which employ several keys similar to a coupler key for effecting the necessary connection between the yoke acting links and the drawbar.

From the preceding description, it will be seen that in carrying out my improvements the only additional expense in the manufacture of the stop lugs or attachment plates as the case may be, is that arising because of the slight amount of additional metal necessary to provide the extensions of the flanges. No additional cost in the application of the stop lug castings or attachment plates is involved, since they are applied in the same manner as heretofore and with the same number of rivets, the punching of the sills remaining as heretofore. Furthermore, with my improvements, I am enabled to use a plain key as distinguished from a headed key, which materially reduces the cost of such keys, since no forging of the ends or drilling for cotter pin holes is required and, the keys may be cut in suitable lengths from plain bars.

While my improvements are probably most advantageously used in connection with plain or unheaded keys as illustrated, nevertheless it will be understood that my improvements are equally effective if used with keys of the headed type, in which event it is only necessary to use retaining means adjacent the headed ends of the keys.

While I have herein shown and described the preferred manner of carrying out my invention, the same is merely illustrative and I contemplate all changes and modifications that come within the scope of the claims appended hereto.

I claim:

1. In a retaining means for a connecting key of a draft rigging, wherein the key extends transversely of the sills and has one end

- thereof projecting outwardly beyond the plane of one sill through a slot therein; the combination with a casting of the draft rigging secured to one face of said sill, said casting having a flanged section fitting within said slot of the sill and having a portion of said flanged section projecting outwardly of the plane of the sill beyond the adjacent end of the key; of means supported solely by said projecting portion having a free end overlapping the adjacent end of the key to prevent accidental removal of said key from the corresponding side of the draft sills, said free end always overlapping a portion of said end of the key in any longitudinal position of the latter while in said slot. 5
2. In a retaining means for a connecting key of a draft rigging, wherein the key extends transversely of the sills and has one end thereof projecting outwardly beyond the plane of one sill through a slot therein, the combination with a casting of the draft rigging secured to one face of said sill, said casting having a flanged section fitting within said slot of the sill and having said flanged section projecting outwardly of the plane of the sill beyond the adjacent end of the key; of holding means supported by said outwardly extended flanged section of the casting, 20 said means having a depending abutment section opposed to said end of the key to prevent accidental removal of said key from the corresponding side of the draft sills, said section at all times overlapping a portion of said end of the key in any longitudinal position of the latter while in said slot. 25
3. In a retaining means for a connecting key of a draft rigging, wherein the key extends transversely of the sills and has one end thereof projecting outwardly beyond the plane of one sill through a slot therein, the combination with a casting of the draft rigging secured to one face of said sill, said casting having a flanged section fitting within said slot of the sill and having said flanged section projecting outwardly of the plane of the sill beyond the adjacent end of the key; of a bendable holding element supported by said outwardly extended flanged section of the castings said element being bendable to bring a section thereof into overlapping relation to said end of the key, thereby providing an abutment opposite said end of the key to prevent accidental removal thereof 45 50
- from the corresponding side of the draft sills, said section at all times overlapping the portion of said end of the key in any longitudinal position of the latter while in said slot. 55
4. In a railway draft rigging, the combination with center sills having key receiving openings and a key working in said opening; of an inherently bendable retaining element having one end rigidly supported from the outer side of one center sill and having a portion disposed outwardly of and overlapping the corresponding end of the key and adapted to limit endwise movement thereof in one direction. 60 65
5. In a railway draft rigging, the combination with center sills having aligned key receiving openings reinforced by flanged members, a key working in said reinforced openings, the ends of said key terminating inwardly of the outer edges of the flanges of said members; of a pair of angular retaining elements carried by the flanges of said members, said elements having depending flanges disposed outwardly of the corresponding ends of the key, said depending flanges forming abutment means for limiting endwise displacement of the key. 70 75 80
6. In a railway draft rigging, the combination with opposed draft sills having aligned key receiving openings and a connecting key working in said openings; of a fixed retaining element cooperating with an end of the key, said element having a depending section overhanging said end of the key to prevent accidental removal of the key from the corresponding side of the draft sills. 85 90
7. In a railway draft rigging, the combination with opposed draft sills having aligned key receiving openings and a connecting key working in said openings; of a fixed retaining element cooperating with an end of the key, said element having a depending section overhanging said end of the key to prevent accidental removal of the key from the corresponding side of the draft sills, said element being bendable whereby said section may be displaced to one side of the key to permit removal of the latter from the corresponding side of the draft sills. 95 100 105

In witness that I claim the foregoing I have hereunto subscribed my name this 10th day of October, 1925.

JOSEPH HARRIS.
